UNITED STATES PATENT OFFICE.

BENJAMIN F. SHAKESPEARE, OF CHESTER, PENNSYLVANIA.

METHOD OF AND APPARATUS FOR REFRIGERATING PARAFFINE AND OTHER OILS.

SPECIFICATION forming part of Letters Patent No. 291,632, dated January 8, 1884.

Application filed May 26, 1883. (No model.)

To all whom it may concern:

Be it known that I, BENJAMIN F. SHAKESPEARE, a citizen of the United States, residing at the city of Chester, in the county of Delaware and State of Pennsylvania, have invented certain new and useful Improvements in the Method of and Apparatus for Refrigerating Paraffine and other Oils, of which the following is a full, clear, and exact description, reference being had to the accompanying drawings.

The general nature and purpose of this invention are indicated by its title. Its object, specifically, is to provide an improved means for securing in an economical manner the continuous and rapid congelation or refrigeration of the oil (or distillate) in the manufacture of paraffine, although it is applicable in connection with other oils whose temperature it may be desired to quickly reduce. Such oils being bad conductors of heat, there is required, under ordinary conditions and with the means and devices heretofore in vogue or known to me, a comparatively long time to sufficiently chill them. I accomplish the object stated by bringing together, by means of a suitable apparatus, the warm oil and a refrigerating fluid—usually brine brought artificially to a low temperature—while finely divided and in motion, or more or less in the form of spray.

I shall now proceed to describe an organized apparatus and the *modus operandi* which I have designed to effect this purpose, reference being had to the accompanying drawings, of which—

Figure 1 is a side elevation, partly in section, of such apparatus; and Fig. 2 is a view, looking from beneath, of the system of oil and cold-water-spraying pipes located over the receiver, D, Fig. 1, placed for the reception of the falling water and congealed oil.

A is the tank, in which the heated oil is contained. O is a pipe leading therefrom, and having a series of laterally-projecting pipes, o, extending horizontally over a receiver, D. These lateral pipes are closed at their free ends, but are pierced with a number of small orifices, x, Fig. 2, on their lower sides, through which the oil flowing from the tank A escapes in numerous streamlets.

W is a cold water or brine supply pipe connecting with a force-pump, P, and extending alongside, and in the present instance below, the oil-pipe O. It also is provided with a number of laterally-extending pipes, w, having series of small perforations, y, similar to those of the oil-pipes o. These water-pipes are arranged so as to alternate with the oil-spraying pipes, and their orifices y constitute two rows placed, respectively, a little to the sides of the pipes, as shown, whereby the opposite rows of streamlets are caused to bisect each other, and also those flowing from the oil-pipes, as illustrated in Fig. 1. The streams of cold water and of warm oil becoming thus broken up by the force of their impact together, and a large surface of the refrigerating fluid being thus brought into close contact with the globules of oil, it is obvious that the latter will quickly chill and the solidified paraffine fall in small granules, q, with the water into the receiving-tank D, the paraffine floating on top of the water, all as seen in Fig. 1. The water or brine escapes through openings l in the bottom of receiver D into a receptacle, F, wherein it may again be reduced in temperature by any suitable means before finding its way into the wells H and I through the pipes J and K, from which wells it is pumped back by pump P through pipe W, and so on indefinitely.

It is usually preferred to have two wells or cisterns, so that they may be pumped from alternately. While the water which has acquired heat from the warm oil, in the act of refrigerating the latter, as hereinbefore described, is flowing into one of the said wells, the pump is taking water previously allowed to flow into the other well from the same source, and which has been permitted to cool or has been artificially cooled in the latter. This may be regulated by means of stop-cocks S in pipe J delivering into the first well H, and in pipe K, leading into the second well I, together with cocks S' in pipes M and N, connecting the force-pump and the wells H and I, respectively.

I am aware of the fact that oily liquids have been congealed by allowing the same to fall from one vessel into another containing ice-water in numerous small streams, instead of in

a single large stream, as customary. I do not, therefore, claim that as being covered by my present invention.

Having thus described my invention, I claim 5 as new and useful and desire to secure by Letters Patent—

1. The improved method or process of producing the congelation or cooling of paraffine and other oils, which consists in bringing together the oil and a refrigerating liquid, both in a spray or comminuted condition, substantially as and for the purpose set forth.

2. The improved method or process of rapidly reducing the temperature of oils, which 15 consists in forcing against a small body or bodies of oil in motion a series of streamlets of a refrigerating fluid, whereby the said fluids are caused to be broken up into small particles, or into a spray, substantially as and for the 20 purposes set forth.

3. An apparatus for congealing paraffine and other oils, consisting of the following elements, combined, constructed, and operating substantially as and for the purposes set forth, 25 viz: An oil-supply pipe or pipes having a series of small orifices therein, a cold-water-supply pipe or pipes, also with a series of small orifices therein, the said oil and water pipes and their orifices being relatively located, as 30 shown and described, so as to cause the streams of oil and water issuing from said pipes, respectively, to impinge against each other, together with means, substantially as described, 35 for forcibly directing the one series of streams against the other.

4. In an apparatus for quickly congealing or reducing the temperature of paraffine and other oils, the combination of a system of oil-supply pipes provided with series of small 40 orifices, and cold-water-supply pipes with

similar orifices, the respective pipes and orifices therein being relatively located, as shown and described, a force-pump for forcing the water out of the orifices in the said water-pipes, and a receiving-tank beneath the system of oil and water pipes, all constructed, combined, and operating substantially as and for the purposes set forth. 45

5. In an apparatus for congealing or reducing the temperature of paraffine and other oils, 50 the combination of a system of perforated oil-pipes and cold-water pipes, the perforations of the said pipes being combined and arranged with relation to each other as shown and described, whereby the opposite streams of water 55 are caused to bisect each other, and also the intermediate streams of oil, together with means for forcibly ejecting the water from said water-pipes, the combination, arrangement, and operation being substantially as 60 shown and described.

6. The oil-conduit, with lateral horizontal pipes *o*, the cold-water pipe with lateral horizontal branches *w*, alternating with pipes *o*, as shown, and provided with the orifices *x* and 65 *y*, respectively, the receiver *D*, the well or wells, with pipes for conveying the water from the receiver to the wells, the pump *P*, with pipes communicating with said wells, all combined, constructed, arranged, and adapted to 70 operate substantially as and for the purposes set forth.

In testimony whereof I have hereunto affixed my signature this 20th day of March, A. D. 1883.

BENJAMIN F. SHAKESPEARE.
